UNITED STATES PATENT OFFICE.

HENRY B. MATTHEWS, OF NEW YORK; ASSIGNOR TO M. H. BIRGE & SONS, OF BUFFALO, NEW YORK.

DESIGN FOR WALL-PAPER.

SPECIFICATION forming part of Design No. 23,622, dated September 4, 1894.

Application filed August 10, 1894. Serial No. 519,977. Term of patent 3½ years.

To all whom it may concern:

Be it known that I, HENRY B. MATTHEWS, a subject of the Queen of Great Britain, residing at New York, in the county and State of New York, have invented and produced a new and original Design for Wall-Paper, of which the following is a specification.

The design consists of an arrangement of ornamental scrolls and breast plates with eagles 10 perched upon the breast plates and ribbon festoons hanging from the eagles' beaks as represented in the accompanying drawing. The border is also formed of the same design with a narrow ornamental band at the bottom separating the border from the hanging as shown in the drawing.

What I claim is—

1. The design for wall paper herein shown and described.
2. In the design for wall paper, the border herein shown and described.

Witness my hand this 8th day of August, 1894.

HENRY B. MATTHEWS.
